UNITED STATES PATENT OFFICE

161,272

DINNER PLATE OR SIMILAR ARTICLE

Charles H. McKaig, Camillus, N. Y., assignor to Onondaga Pottery Company, Syracuse, N. Y., a corporation of New York

Application November 4, 1949, Serial No. 5,855

Term of patent 14 years

(Cl. D44—15)

To all whom it may concern:

Be it known that I, Charles H. McKaig, a citizen of the United States, residing at Camillus, in the county of Onondaga and State of New York, have invented a new, original, ornamental Design for a Dinner Plate or Similar Article, of which the following is a specification, reference being had to the accompanying drawing, forming part thereof.

The drawing is a plan view of a plate of conventional configuration showing my new design. The dominant feature of the design resides in the ornamentation shown on the plate.

I claim:

The ornamental design for a dinner plate or similar article, as shown and described.

CHARLES H. MCKAIG.
